UNITED STATES PATENT OFFICE.

DAD BOYLE, OF AMARILLO, TEXAS.

DESIGN FOR A WAGON-BODY.

40,878.

Specification for Design.

Patented Sept. 13, 1910.

Application filed November 1, 1909. Serial No. 525,828. Term of patent 14 years.

To all whom it may concern:

Be it known that I, DAD BOYLE, a citizen of the United States, residing at Amarillo, in the county of Potter and State of Texas, have invented a new, original, and ornamental Design for Wagon-Bodies, of which the following is a specification, reference being had to the accompanying drawing, forming a part thereof.

Figure 1 is a side elevation of a wagon body embodying my design. Fig. 2 is a side view shown slightly in perspective, the same showing the opposite side of the wagon body to that shown in Fig. 1. Fig. 3 is a front view. Fig. 4 is a rear view.

The design of my wagon body discloses a door in one side, together with a plurality of windows arranged for attracting the eye,

while the opposite side of the wagon is arranged with a plurality of windows, a door, and a plurality of show cases associated together for presenting means which attract. The opposite ends of the wagon body are arranged with windows and panels to harmonize with the windows and associated parts of the sides for presenting a harmonious arrangement when taken with what might be termed a double deck top formed with curving lines.

I claim;

The ornamental design for a wagon body as shown and described.

DAD BOYLE.
